(57) **CLAIM**

The ornamental design for an earphone, as shown and described.

DESCRIPTION

FIG. 1 is a top perspective view of an earphone of the present design;

FIG. 2 is a bottom perspective view of the earphone of the present design;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is top view thereof;

FIG. 9 is enlarged view of a portion of the earphone shown within the area designated as 9 in FIG. 1;

FIG. 10 is enlarged view of a portion of the earphone shown within the area designated as 10 in FIG. 1;

FIG. 11 is enlarged view of a portion of the earphone shown within the area designated as 11 in FIG. 1;

FIG. 12 is enlarged view of a portion of the earphone shown within the area designated as 12 in FIG. 1;

FIG. 13 is enlarged view of a portion of the earphone shown within the area designated as 13 in FIG. 1;

FIG. 14 is enlarged view of a portion of the earphone shown within the area designated as 14 in FIG. 2;

FIG. 15 is enlarged view of a portion of the earphone shown within the area designated as 15 in FIG. 2;

FIG. 16 is enlarged view of a portion of the earphone shown within the area designated as 16 in FIG. 2;

FIG. 17 is enlarged view of a portion of the earphone shown within the area designated as 17 in FIG. 2; and,

FIG. 18 is enlarged view of a portion of the earphone shown within the area designated as 18 in FIG. 2.

(Continued)

The broken lines in the figures depict portions of the earphone that form on part of the claimed design. The dashed broken lines encircling portions of the earphone in FIGS. 1-2 and illustrated in enlarged views in FIGS. 9-18 form no part of the claimed design.

1 Claim, 18 Drawing Sheets
